COIN BOX-BILLFOLD

Rachel L. Rising, Los Angeles, Calif.

Application December 28, 1953, Serial No. 400,692

3 Claims. (Cl. 150—35)

Generally speaking, the present invention relates to a combined billfold and purse and more particularly, to a combined foldable wallet and coin box-purse having, in addition to a foldable wallet, a box or container sliding in and out of a U frame so as to provide easy access thereto without the necessity of opening the wallet into its fully elongated position in order to secure coins, pills, or the like, and without having to dig down deep into a purse, or the like in the customary prior art manner.

I am aware of the fact that a number of prior art combined purses and billfolds have been invented and developed heretofore. However, none of these prior art arrangements operate to produce the highly desirable results of the present invention, and they all have disadvantages of one type or another.

For example, all of such prior art combined billfolds and purses known to me expand unevenly resulting in an irregular, unsymmetrical pile when coins, pills, or the like, are placed in them, creating a bulky and clumsy combined billfold and purse difficult to fasten when folded about a central transverse fold line. Therefore, they are not frequently used under the circumstances set forth hereinabove because of their unsuitability for such use.

All of the prior art combined billfold-purses, which are known to me, are of a type wherein a person cannot easily see the various coins, pills or the like, carried therein, and they cannot easily be moved around in a tightly closed confined region such as is usually found in the purse portion of such a prior art combined billfold-purse. This arrangement is unsatisfactory and undesirable because it does not allow the easy locating of the aforesaid items. It will usually be necessary for the person to first manually unfasten the billfold-purse, then to unfold the billfold-purse into its completely elongated position, then to open the purse portion thereof, then to spread it open as far as its physical limits permit, then to search and extract the item desired, then close the purse portion, then refold the billfold-purse about its central transverse fold line, and finally to refasten the snap or other means, frequently provided to keep the billfold-purse from reopening. This series of operations, which occurs many times during the day, is undesirable, annoying and frustrating. Another major disadvantage of this arrangement is that the unevenly distributed coins, pills and the like, in the purse portion cause a loss of usable space by reason of being bulky and clumsy when carried in a handbag or a pocket.

Generally speaking, the improved billfold-purse of the present invention includes a drawer, box or container slidably mounted in a pocket at the open (non-folded) end of the billfold-purse and capable of being slidably opened without having to unfold the closed billfold-purse into its fully elongated position. Said drawer, container or box holds coins, pills, or the like, in a relatively symmetrically distributed manner and prevents the aforesaid items from piling upon one edge of the purse portion of the billfold-purse and thus creating a bulky region. Also, coin ingress means into said box or container may be provided; said coin ingress means being accessible from the exterior of said pocket for pushing in loose coins received as change.

The present invention may also include travel-limiting means effectively cooperable with respect to said drawer

2

and with respect to said billfold-purse to effectively act as a stop to prevent said drawer, container or box from being pulled out completely from said pocket whereby to prevent the drawer, container or box from falling and spilling its contents onto the floor, or other underlying surface.

The present invention may, also, be supplied with manually operable fastening means effectively cooperable with respect to the drawer, container or box for selectively, effectively, locking and unlocking said drawer, container or box with respect to said pocket.

From the above description of a basic and several preferred generic forms of the present invention, it will be apparent to those skilled in the art that virtually all of the hereinabove-mentioned disadvantages of prior billfold-purses are virtually entirely eliminated and/or overcome in and through the use of the present invention.

For example, the billfold-purse of the present invention is small, light, and cheap and portable and portions of the pocket containing the drawer, container or box may, if desired, be made of plastic material, or the like, that is translucent, semi-transparent or opaque, so that if preferred, the contents may be visually inspected from the exterior thereof with a minimum of difficulty because the contents are relatively distributed (or distributable) within said drawer.

Furthermore, it is not necessary to go through the hereinbefore-mentioned sequence of operations of opening the billfold-purse to remove the contents of the purse portion thereof, and then going through further manual operations of closing said purse portion, folding the billfold-purse, and then snapping it closed with a fastener, or the like. It is only necessary to open the fastening means and look for the desired item; if it is not there, you simply refasten the fastening means; if the item desired is there, you simply slide out the drawer, container or box and immediately place your fingers on the desired item. Thus, the device of the present invention provides for immediate positive identification and location of the desired item contained within the container or box and makes it simple and convenient for all persons utilizing this device.

With the above points in mind, it is an object of the present invention to provide a portable billfold-purse capable of rapid, easy and simple operation, and including a novel drawer adapted for use as a purse with great benefit in time-saving in re the securing of a coin, pill, or the like, from within said purse.

It is a further object of the present invention to provide a simple, cheap, small, light, portable, safe, convenient billfold-purse arranged to carry coins, pills, and the like, without creating a bulky or clumsy region within the aforesaid billfold-purse caused by an aggregation of said coins.

Other and allied objects will be apparent to those skilled in the art after a careful perusal, examination and study of the accompanying illustrations, the present specification, and the appended claims.

To facilitate understanding, reference will be made to the hereinbelow-described drawings, in which:

Fig. 1 is a perspective view showing one form of combined billfold-purse in an unfolded position.

Fig. 2 is an exploded perspective view similar in aspect to Fig. 1.

Fig. 3 is a fragmentary, partially broken-away, perspective view similar in aspect to Fig. 1, but shows the drawer in partially extended position.

Fig. 4 is a fragmentary end elevation of a slightly modified form of drawer having coin ingress means.

Fig. 5 is a fragmentary, partial vertical section taken in the direction of the arrows V—V in Fig. 4.

Generally speaking, the foldable wallet and coin box-

purse of the present invention comprises at least three flexible wall members secured together to form an elongated pocket and a closely adjacent superimposed short pocket, with said elongated pocket being provided with longitudinal opening means adjacent one of its long side edges to provide side access thereto, and with said short pocket being provided with port means adjacent one of the wallet's short end edges to provide end access thereto.

In the specific form of the present invention illustrated in Figs. 1, 2 and 3, the flexible wall members include two similar, virtually rectangular, flexible wall members 1 and 2 secured together along one long side edge 3 thereof, and along two end edges 4 and 5 to define an elongated pocket between the wall members 1 and 2 having a longitudinal opening means comprising the zipper 6 adjacent the other long side edge 7 to provide side access into said elongated pocket. In the specific example illustrated, said flexible wall members also include an auxiliary rectangular wall member 8 also fastened at the edges 3, 4 and 5 in a manner similar to the edge-fastening of the wall members 1 and 2, but not fastened at an edge 9 closely adjacent to and virtually parallel with respect to the zipper 6, thus providing a second auxiliary elongated pocket provided with longitudinal access means thereinto defined by the opening between the edge 9 of the wall member 8 and the surface of the adjacent wall member 2. Both this elongated pocket and the first above-mentioned elongated pocket are adapted to receive flat foldable objects (such as paper money, or the like) therein for storage purposes.

The above generally referred to flexible wall members also include, in the specific example illustrated, an additional, virtually rectangular, flexible wall member 10 suitably connected, as by sewing or the like, to a portion of the long side edge 3 and to a similar portion of the flexible wall 8 along a line 11 so positioned as to allow access to the zipper 6, and also connected such as by sewing and the like, to the wall member 8 in a transverse direction adjacent the center fold line 12 whereby to define a short pocket, indicated generally at 13, provided with port means 14 thereinto. This is best shown in Fig. 2.

Also, generally speaking, the present invention includes a drawer-receiving frame including two virtually parallel, laterally spaced, side frame members connected at their rear ends by a laterally directed rear frame member, said frame having a drawer-receiving opening at the front end between said two side members, and said frame being mounted within said short pocket with said drawer receiving opening aligned with said port means.

In the specific example illustrated, the drawer-receiving frame is indicated generally at 15 (as best seen in Fig. 2) and includes two side frame members 16 connected at their rear ends by a laterally directed rear frame member 17. The arrangement is such that the front ends of the side frame members 16 effectively define a drawer-receiving opening, indicated generally at 18, therebetween (as best seen in Fig. 2). The frame 15 is adapted to be moved from the position shown in Fig. 2 into the position shown in Fig. 1, by inserting said frame 15 through the port 14 into the short pocket 13 and suitably mounting it therein (such as by mechanical fastening means, or the like).

The present invention also includes a drawer defining a storage region therein, said drawer being slidably cooperable within the frame and within the short pocket for manual insertion thereinto and for manual extension outwardly therefrom.

In the specific example illustrated, one such drawer is indicated generally at 19 and includes the customary four edge walls 20 in upstanding relationship with respect to the customary flat bottom wall 21, thus defining a storage region 22. In the example illustrated, a finger tab 23, to facilitate extension of the drawer 19 with respect to the short pocket 13, is also included. The drawer 19 is

adapted to be moved from the position shown in Fig. 2 into the position shown in Fig. 1 by inserting the rear end of the drawer 19 through the port 14 into the short pocket 13 and the drawer-receiving opening 18 between the frame members 16 for slidable cooperation therewith. In this connection, it should be noted that the drawer 19 is shown in fully inserted relation in Fig. 1 and is shown in partially extended relation in Fig. 3.

Also, generally speaking, the device of the present invention may include travel-limiting means effectively cooperable with respect to the slidably movable drawer and effectively cooperable with the remainder of the wallet to limit the withdrawal of the drawer from the short pocket to an extent so as to prevent complete disengagement thereof.

In the specific example illustrated, (as best shown in Fig. 2) the travel-limiting means is indicated generally at 24 and takes the form of the flexible link 25 fastened at one end to the drawer 19, and adapted to be fastened at its other end with respect to the rear portions of the interior of the short pocket 13 (or to other portions of the wallet) thus comprising means adapted to limit the travel of the drawer 19 during extension thereof in a manner such as is indicated in Fig. 3 whereby the drawer 19 will not become completely disengaged from the frame 15 and will, therefore, not spill the contents of said drawer onto an underlying floor or the like.

The present invention may also be provided with manually operable fastening means effectively cooperable with respect to the drawer for selectively locking said drawer in fully inserted relationship within the short pocket and for selectively unlocking said drawer for extension thereof with respect to said short pocket.

In the specific example illustrated, the fastening means takes the form of a flexible tab 26 carried by the end edge 5 and provided with a snap fastener element 27 adapted to cooperate with a similar snap fastener element 27' carried by the flexible wall member 1 closely adjacent to the opposite end edge 4. In other words, the tab 26 is adapted to fold over and around said opposite end edge 4 to cooperate with said second mentioned snap fastener element 27' positioned on the back side of the wall member 1 just behind the end edge 4, and best seen in broken lines in Fig. 2.

Figs. 4 and 5 illustrate a slightly modified form of the present invention wherein the drawer 19' is provided with coin ingress means, indicated generally at 28, and including a slot 29 in the front edge wall 20' of the drawer 19' and spring means 30 positioned inside the drawer in cooperative relationship with respect to the slot 29 whereby to allow ingress of coins but to prevent egress of coins with respect to the slot 29. It will be understood that, in this form of the invention, the slot 29 will be accessible from the end 4 of the wallet when it is in folded position adjacent the other end 5, by merely unfastening the tab 26 (shown in Figs. 1, 2 and 3) so as to effectively uncover the slot 29.

In certain forms of the present invention, at least certain portions of the short pocket 13 (usually, portions of the wall member 10) may be semi-transparent or transparent so as to make visual inspection of the contents of the drawer 19 possible from the exterior of the pocket 13 prior to extension of the drawer 19 therefrom. This is indicated in Fig. 1 by the reference numeral 31 which lies in the area directly over the storage region in the drawer 19.

Numerous modifications and variations of the present invention will occur to those skilled in the art after a careful study hereof. All such properly within the basic spirit, scope and teachings of the present invention are intended to be included and comprehended herein as fully as if specifically described, illustrated and claimed herein.

For example, it should be noted that the wall member 8 (and the extra elongated pocket defined thereby) can be eliminated entirely, if desired, and the short pocket

wall member 10 can be affixed directly to the wall member 2. It should also be noted that the zipper closure means can be eliminated, if desired. Additional pockets, either long or short, may be incorporated, if desired. The travel-limiting means can be modified substantially or, in certain cases, eliminated entirely—this is also true of the fastening means.

The drawer-receiving frame can also be modified substantially within the spirit of the present invention. The coin ingress means can be modified substantially or differently located with respect to the drawer. It should also be noted that the position of the drawer may be inverted, if desired, so that the adjacent wall forming part of the elongated pocket will actually act as a cover for the storage region within the drawer, thereby making it possible to eliminate the wall 10 and merely retain the drawer by means of the frame.

The exact compositions, configurations, constructions, relative positionings, and cooperative relationships of the various component parts of the present invention are not critical, and can be modified substantially within the spirit of the present invention.

The embodiments of the present invention specifically described and illustrated herein are exemplary only, and are not intended to limit the scope of the present invention, which is to be interpreted in the light of the prior art and the appended claims only, with due consideration for the doctrine of equivalents.

I claim:

1. A combined foldable wallet and coin box-purse having two short end edges and two long side edges, each of said side edges being adapted to be folded upon itself for effective closure of the wallet, comprising: at least three flexible wall members secured together to form an elongated pocket and a closely adjacent superimposed short pocket; said elongated pocket being provided with longitudinal opening means adjacent one of the long side edges to provide side access thereto; said short pocket being provided with port means adjacent one of said short end edges to provide end access thereto; a drawer-receiving frame including two parallel, laterally spaced side frame members connected at their rear ends by a laterally directed rear frame member, the space within said frame members defining a drawer-receiving opening at the front end of said frame; said frame being mounted within said short pocket with said drawer-receiving opening aligned with said port means; a drawer defining a storage region therein, said drawer being closely slidably cooperable within the frame and within the short pocket for manual insertion thereto and for manual extension thereof outwardly from said short pocket whereby to provide selective access into said storage region within said drawer.

2. A rectangular, combined foldable wallet and coin box-purse having two short end edges and two long side edges, each of said side edges being adapted to be folded upon itself for effective closure of the wallet, comprising: at least three flexible rectangular wall members secured together to form an elongated rectangular pocket and a closely adjacent superimposed short rectangular pocket; said elongated pocket being provided with longitudinal opening means adjacent one of the long side edges to provide side access thereto; said short pocket being provided with port means adjacent one of said short end edges to provide end access thereto; a rectangular drawer-receiving frame including two parallel, laterally spaced side frame members connected at their rear ends by a laterally directed rear frame member, the space within said frame members defining a drawer-receiving opening at the front end of said frame; said frame being mounted within said short pocket with said drawer-receiving opening aligned with said port means; a drawer defining a storage region therein, said drawer being closely slidably cooperable within the frame and within the short pocket for manual insertion there-

into and for manual extension thereof outwardly from said short pocket whereby to provide selective access into said storage region within said drawer; manually operable fastening means respectively secured to and carried by said wall members adjacent said short end edges and selectively fastenable together to fasten said short end edges in closely adjacent relation thereby locking said drawer in fully inserted relationship within said short pocket and selectively unfastenable thereby unlocking said drawer for extension thereof into non-fully inserted relationship to said short pocket; and travel-limiting means including a flexible link connected at one end to said drawer and connected at the other end in effectively fixed relationship to the short pocket to limit the possible withdrawal of the drawer from said short pocket to an extent such as to prevent complete disengagement thereof, said drawer being provided with a portion defining a coin ingress opening in effective communication with the storage region within the drawer, said coin ingress opening being accessible from the exterior of the short pocket.

3. A rectangular, combined foldable wallet and coin box-purse having two short end edges and two long side edges, each of said side edges being adapted to be folded upon itself for effective closure of the wallet, comprising: at least three flexible rectangular wall members secured together to form an elongated rectangular pocket and a closely adjacent superimposed short rectangular pocket; said elongated pocket being provided with longitudinal opening means adjacent one of the long side edges to provide side access thereto; said short pocket being provided with port means adjacent one of said short end edges to provide end access thereto; a rectangular drawer-receiving frame including two parallel, laterally spaced side frame members connected at their rear ends by a laterally directed rear frame member, the space within said frame members defining a drawer-receiving opening at the front end of said frame; said frame being mounted within said short pocket with said drawer-receiving opening aligned with said port means; a drawer defining a storage region therein, said drawer being closely slidably cooperable within the frame and within the short pocket for manual insertion thereto and for manual extension thereof outwardly from said short pocket whereby to provide selective access into said storage region within said drawer; manually operable fastening means respectively secured to and carried by said wall members adjacent said short end edges and selectively fastenable together to fasten said short end edges in closely adjacent relation thereby locking said drawer in fully inserted relationship within said short pocket and selectively unfastenable thereby unlocking said drawer for extension thereof into non-fully inserted relationship to said short pocket; and travel-limiting means including a flexible link connected at one end to said drawer and connected at the other end in effectively fixed relationship to the short pocket to limit the possible withdrawal of the drawer from said short pocket to an extent such as to prevent complete disengagement thereof; at least a portion of the wall members defining said short pocket being light-transmissive to render the storage region within the drawer in said short pocket visible from the exterior thereof, said drawer being provided at its outer end with a portion defining a coin ingress slot in effective communication with the storage region within the drawer, said coin ingress slot being accessible from the exterior of the short pocket.
